UNITED STATES PATENT OFFICE.

HORACE D. JONES, OF CINCINNATI, OHIO, ASSIGNOR OF ONE-HALF TO
F. SNODGRASS, OF DELAWARE, OHIO.

DESIGN FOR A HAT-HOLDER.

SPECIFICATION forming part of Design No. 31,481, dated August 29, 1899.

Application filed August 4, 1899. Serial No. 726,202. Term of patent 14 years.

To all whom it may concern:

Be it known that I, HORACE D. JONES, a citizen of the United States, residing at Cincinnati, in the county of Hamilton and State of Ohio, have invented and produced a certain new and original Design for Hat-Holders; and I do declare the following to be a full, clear, and exact description of the invention, such as will enable others skilled in the art to 10 which it appertains to make and use the same.

The invention relates to a new and original design for hat-holders; and it consists of a design of the configuration and ornamentation shown in the accompanying drawings, in 15 which—

Figure 1 is a perspective view. Fig. 2 is a side elevation. Fig. 3 is a top plan view.

The leading features of my design comprise a vertical support 1, arms 2 and 3, arranged

at right angles to each other and consisting 20 of radially-extending members *a*, the ends of which are curved upward and inward, as shown at *b*, thence inclined upward, as shown at *c*, and thence terminating in a semicircular portion *d*, the semicircular portion of one 25 member being located under the semicircular portion of the other member.

What I claim is—

The design for a hat-holder, as herein shown and described.

In testimony whereof I have hereunto set my hand in presence of two subscribing witnesses.

HORACE D. JONES.
